UNITED STATES PATENT OFFICE.

VICTOR SENCE, OF NEW YORK, N. Y.

ELECTRIC BELT.

No. 895,506.

Specification of Letters Patent.

Patented Aug. 11, 1908.

Application filed June 6, 1907. Serial No. 377,514.

To all whom it may concern:

Be it known that I, VICTOR SENCE, a citizen of the United States of America, and a resident of the borough of Manhattan, city, county, and State of New York, have invented certain new and useful Improvements in Electric Belts, of which the following is a specification.

My invention relates to electric belts in general and more specifically comprises means for rapidly opening and closing the electric circuit in such belts in order to produce a pulsatory current therein.

Heretofore electric belts have been employed, such for instance as that shown in Patent 638,148 to Albert T. Sanden, dated Nov. 28, 1899, in which a flexible band or easing supports a series of small cells of electric battery which are connected together in series, one terminal of one end of the last cell being connected to a terminal or pad adapted to press upon the body of the wearer at one point and the other element of the last cell at the other end of the belt being connected to another terminal or pad adapted to press upon the body of the wearer at another point, whereby a complete electric circuit is created through the belt and the body of the wearer, through which circuit a continuous electric current generated by the cells of a voltaic battery is sent.

I find that it is desirable to rapidly open and close the circuit in such belts so as to change the continuous current heretofore used into a pulsatory current. I have invented a convenient form of apparatus for carrying out this improvement, which together with one modification is illustrated in the accompanying sheet of drawings, in which:

Figure 1 is a perspective view of an electric belt with my invention embodied therein, parts being broken away. Fig. 2 is an enlarged detail of a vibrating switch driven by clock work, indicated in Fig. 1, and Fig. 3 is an enlarged detail of an electrically operated vibrator or switch for automatically opening and closing the circuit with great rapidity.

Throughout the drawings like reference figures indicate like parts.

1 is the belt cover or band, and 2 and 3 are two terminals or pads carried by said belt, preferably at a point adapted to press upon the back of the wearer.

4 is another pad carried by the buckle strap 5 adapted to be attached to the belt so

as to press upon the front of the wearer's body.

The belt band 1 carries a series of electric voltaic battery cells, one element of which cells is represented by 6, 6, while wires 7, 7, 60 represent the terminals of the other elements of the battery cells. As shown, these cells are connected up in series and the wire 8 extends from the last battery element 6 at one end of the belt to the pad 4, while metallic 65 connection 9 extends from the wire connection 7 of the last cell at the other end of the belt to the frame 10 of clock work.

The form of swinging switch and vibrating mechanism shown in Figs. 1 and 2, comprises 70 the metallic frame 10 of a clock work carrying the clock train 11 of any desired construction having the usual escapement lever 12. 13 is a bifurcated contact mounted in insulation 14, carried on the main frame 10. 15 75 is a binding post on the exterior of the casing of the clock work connected to the contact 13. 16 is a wire or other conducting connection from the binding post 15 to the pads 2 and 3. 17 is the key for winding up the 80 spring of the clock train.

The method of operation of my invention so far described is as follows: The cells of the battery being filled with the proper active material or liquid, the belt is adjusted about 85 the person of the wearer and connected as shown in Fig. 1. This causes a current to circulate through the connections in the belt and from pads 2 and 3 through the body of the wearer to the pad 4 or in the opposite direction according to the arrangement of the battery cells. If now, the spring of the clock work is wound up by means of the key 17, the mechanism will be set in operation and the escape lever 12 will become a swinging switch vibrating between the two sides of the bifurcated contact 13. It is evident 90 that this will rapidly open and close the circuit and change the continuous current into a rapidly pulsating current.

In the modified mechanism shown in Fig. 3, 18 is the magnet of an ordinary electric buzzer having the armature 19, contact screw 20, buzzer circuit 21 in which is included a small cell of dry battery 22, and the controlling switch 23. The main frame 27 on which the before described parts are mounted contains two insulated contacts 24, 24, serving as terminals for an opening or break in the wire 16. 25 is an insulated bridge piece 100

carried by an extension from armature 19, and 26 represents insulation properly disposed to preserve the integrity of the circuit through wires 16 and 21.

5 In operation this device would be substituted for the clock work train previously described and would control the circuit through wire 16. When the switch 23 is open, as shown in Fig. 3, the bridge piece 25 would 10 complete the circuit through wire 16. Then the switch 23 is closed, the magnet 18 and battery 22 would come into action and rapidly vibrate the armature 19 in the manner of the ordinary buzzer, thereby alternately 15 withdrawing the bridge piece 25 from contact with the terminals 24, 24, and returning it to such contact, thereby opening and closing the circuit to the electric belt apparatus at a high rate of speed and producing corresponding 20 pulsations of the current to pass through the body of the wearer.

The advantages of my invention comprise the improved result on the patient produced by substituting the pulsating current for continuous current, the compact construction of the switch apparatus and its ready adaptability to the form of electric belt now on the market.

25 The current necessary for an electrical belt must be of fairly high voltage in order to produce therapeutic results, but it must be of very low amperage or quantity in order not to produce inflammation of the skin at the point of contact with the electrodes. The 30 cells of voltaic battery here shown have a voltage of about three quarters of a volt each, and the large number of them connected up in series gives the necessary voltage. The amperage is so small, however, that no form 35 of magnetically operated circuit breaker can be actuated by it. Hence I prefer the clock work circuit breaker shown in Fig. 2 of the drawings for this and other reasons. A magnetically operated circuit breaker actuated 40 by a separate cell of dry battery of sufficient amperage might be substituted for the clock work circuit breaker if desired, or a small cell of storage battery might be used. In these cases the current going through the patient's 45 body would still be generated solely by the cells of voltaic battery in the belt while the low voltage, high amperage current of the other battery would be used solely to open and close the magnetic circuit breaker.

50 Having, therefore, described my invention, I claim:

1. In an electric belt the combination with two terminal pads carried by said belt adapted to rest in contact with the body of the 55 wearer at opposite points of said body, of a circuit of conductive material connecting said pads, a series of small voltaic cells included in said circuit in series, a switch in

said circuit, mechanism for opening and closing said switch and means for operating 60 said mechanism separate from the voltaic current generated by the belt cells.

2. In an electric belt the combination with two terminal pads carried by said belt adapted to rest in contact with the body of the 70 wearer at opposite points of said body, of a circuit of conductive material connecting said pads, a series of small voltaic cells included in said circuit in series, a switch in 75 said circuit, mechanism for opening and closing said switch and means for operating said mechanism separate from the voltaic current generated by the belt cells, said means comprising a clock work mechanism.

3. In an electric belt, the combination with two terminal pads carried by said belt and adapted to rest in contact with the body of the wearer at opposite points of said body, of a series of voltaic battery cells carried by 80 said belt and having the positive pole of one cell connected to the negative pole of the next, the positive pole of the cell at one end of the belt being connected to one pad and the negative pole of the cell at the other end of the belt being connected to the other pad 85 and means for automatically opening and closing the circuit so formed, said means comprising a swinging switch arm connected to one terminal of the circuit, a bifurcated contact piece between the ends of which said 90 switch arm moves connected to the other terminal of the circuit, and a clock work mechanism for vibrating said switch arm.

4. In an electric belt, the combination with two terminal pads carried by said belt and 100 adapted to rest in contact with the body of the wearer at opposite points of said body, of a series of voltaic battery cells carried by 105 said belt and having the positive pole of one cell connected to the negative pole of the next, the positive pole of the cell at one end of the belt being connected to one pad and the negative pole of the cell at the other end of the belt being connected to the other pad and means for automatically opening and 110 closing the circuit so formed, said means including a vibrator included in the said circuit, and composed of a metallic clock work mechanism to the frame of which one end of said circuit is connected, a bifurcated contact piece to which the other end of the circuit is connected and between the ends of which the escapement lever of the clock work vibrates, and an insulated bearing for said contact piece mounted on the clock work frame. 115

Signed at New York, N. Y. this 21st day of May, 1907.

VICTOR SENCE.
